UNITED STATES PATENT OFFICE.

CHARLES FISHER, OF OAK PARK, ILLINOIS, ASSIGNOR OF ONE-FIFTH TO JOHANNA SEGNITZ,
OF MILWAUKEE, WISCONSIN.

LOCK.

No. 862,065.

Specification of Letters Patent.

Patented July 30, 1907.

Application filed April 7, 1906. Serial No. 310,528.

To all whom it may concern:

Be it known that I, CHARLES FISHER, a citizen of the United States, residing at Oak Park, in the county of Cook and State of Illinois, have invented certain new and useful Improvements in Locks, of which the following is a specification, reference being had to the accompanying drawing, forming a part thereof.

This invention relates more particularly to key locks.

10 The main objects of the invention are to produce a simple and effective lock having few parts, and generally to improve the construction and operation of devices of this class.

15 It consists in certain novel features of construction and in the peculiar arrangement and combinations of parts as hereinafter particularly described and pointed out in the claims.

In the accompanying drawing like characters designate the same parts in the several figures.

20 Figure 1 is an inverted plan view of a lock embodying the present invention; Fig. 2 is a cross section on the line 2, 2, Fig. 1; Fig. 3 is a top or plan view of the lock; Fig. 4 is a longitudinal section on the line 4, 4, Fig. 1, and Fig. 5 is a section on the line 5, 5, Fig. 1.

25 For the purpose of illustration the lock case and keeper are shown as formed integrally with a circular cover *a* and a cylindrical case *b*, portions of which appear in the drawing, but they may be made separate from and attached in any suitable manner to the parts

30 which they are intended to connect, without material change in the construction and operation of the essential parts of the lock. The lock case *c* is formed with two chambers which are arranged transversely to and intersect each other.

35 *d* is a reciprocating bolt, preferably made of generally cylindrical form, and fitted in one of said chambers which is open at one end and closed at the other. The bolt is formed in one side with a longitudinal groove *e* and in an adjoining side with two transverse notches

40 or recesses *f* and *g*, each forming two opposing transverse shoulders. A screw *h* threaded in the case *c* and projecting into the recess *f* serves, by engagement with the shoulders at the ends of said recess, to retain the bolt in the case and to limit its longitudinal move-

45 ment therein. A spiral spring *i* inserted in the bolt chamber and bearing at one end against the closed end of said chamber, and at the other end against the adjacent end of the bolt tends to thrust the opposite end of the bolt out of the case and to hold it in locked

50 position, as shown in Fig. 4.

A barrel *j* fitted to turn in the other chamber of the case is formed with an encircling or peripheral groove or recess to fit or receive one side of the bolt *d*. By

the engagement of the bolt with this recess the barrel is held axially from displacement in the case, while it 55 is left free to turn therein. Within the peripheral recess of the barrel is formed a circular tongue *k* which enters the groove *e* in the bolt and prevents the bolt from turning in the case, while it permits free endwise movement thereof. The barrel is formed with a longitudinal slot *l* opening through its ends and one side thereof, and in this slot a key *m* is fitted, as shown in Fig. 2. The outer end of the barrel is reduced in diameter to fit a contracted opening in the case through which it is exposed, as shown in Figs. 2, 3 and 5. The 60 edge of the case around this opening is notched on one side to permit the insertion of the key when the slot *l* registers with the notch, as shown in Fig. 3. The key is notched or cut away in one edge to clear the inwardly projecting edge of the case at the outer 65 end of the barrel and the adjacent side of the bolt, which serve as wards for the lock, as shown in Fig. 2, and the bit *n* at its end is adapted to enter the notch or recess *g* in the bolt and by engagement with the shoulders at the ends thereof to move the bolt out or in. 70 The part *b* to which the lock is applied has an inturned flange *o* which in the present instance serves as a keeper to engage the bolt *d* when it is projected from the case *c*, but as before stated, the keeper may be made separate from and attached to the part to which it is applied, 75 and may be made of any other form suitable for the purpose.

The bolt *d* may be beveled at its outer end, as indicated by the dotted line on Fig. 4, so as to be sprung automatically into engagement with the keeper *o* in 80 bringing the parts *a* and *b* together, but the bolt is preferably made with two shoulders at the ends of the notch or recess *g* for engagement with the key, so that by turning the key into position to withdraw it from the lock the bolt will be positively moved outward 85 into position to receive the bit *n* in the notch or recess *g* when the key is again inserted in the lock, thereby avoiding the contingency of the bolt sticking in the lock and the notch or recess *g* stopping out of position to receive the bit *n* of the key. 90

The parts of the lock are assembled by first inserting the barrel *j* in its chamber and then inserting the spring *i* and the bolt *d* in the other chamber of the case *c*, the bolt being held against the tension of the spring while the screw *h* is turned into place in the notch 100 or recess *f*. The barrel *j* is held in place in the case by the bolt engaging the peripheral recess therein, and the bolt is prevented from turning and its notches or recesses *f* and *g*, with the shoulders at the ends thereof, are held in their proper relation to the barrel and to 105 the key by the engagement of the tongue *k* with the

groove *e* while the screw *h* retains the bolt in place so that by a single screw that serves as a stop to limit the endwise movement of the bolt, the several parts of the lock, when assembled as above stated, are held 5 together.

Various changes in the details of construction and arrangement of parts may be made in adapting the lock to the various articles and uses to which it is applicable, without materially affecting its essential features 10 or mode of operation and without departing from the principle and intended scope of the invention.

I claim:

1. In a lock the combination of a case having chambers arranged transversely to and intersecting each other, a reciprocating bolt fitted in one chamber and having a shoulder adapted to be engaged by a key, and a slotted key-barrel fitted in the other chamber and having a peripheral recess engaging one side of the bolt, substantially as described. 15
2. In a lock the combination of a case having chambers arranged transversely to and intersecting each other, a reciprocating bolt fitted in one chamber and formed with a longitudinal groove, and a longitudinally slotted key-barrel fitted to turn in the other chamber and formed with a peripheral recess to receive one side of the bolt and with a circular tongue in said recess to engage the groove in the bolt which has a shoulder arranged to be engaged by a key inserted in and turned with the barrel, substantially as described. 20
3. In a lock the combination of a case having chambers arranged transversely to and intersecting each other, a reciprocating bolt fitted in one chamber, a spring interposed between one end of said chamber and the adjacent end of the bolt and tending to thrust the opposite end of the bolt 25 out of the case, and a slotted key-barrel fitted to turn in the other chamber and having a peripheral recess to receive one side of the bolt, which has a shoulder arranged

to be engaged by a key inserted in and turned with the barrel, substantially as described.

4. In a lock the combination of a case having chambers 40 arranged transversely to and intersecting each other, a bolt fitted in one of said chambers and having a recess in one side terminating with opposing transverse shoulders, a removable stop projecting from the case into said recess, and a longitudinally slotted key-barrel fitted to turn in the 45 other chamber and formed with a peripheral recess to receive one side of the bolt, which has a shoulder arranged to be engaged by the bit of a key inserted in and turned with said barrel, substantially as described.

5. In a lock the combination of a case having two chambers arranged transversely to and intersecting each other, a bolt fitted in one of said chambers and having a recess in one side terminating with opposing transverse shoulders, and a longitudinally slotted key-barrel fitted to turn in the other chamber and, having a peripheral recess 55 receiving one side of the bolt, the shoulders on the bolt being arranged to be engaged by the bit of a key when inserted in and turned with said barrel, substantially as described.

6. In a lock the combination of a case having chambers arranged transversely to and intersecting each other, a bolt fitted in one of said chambers and having two recesses each terminating in opposing transverse shoulders, a removable stop projecting through the case into one of said recesses, and a longitudinally slotted key-barrel fitted to turn in the other chamber and having a peripheral recess 60 to receive one side of the bolt, the other recess in the bolt being arranged to receive the bit of a key when inserted in and turned with said barrel to move the bolt by engagement with the shoulders at the ends of said recess, substantially as described. 65

In witness whereof I hereto affix my signature in presence of two witnesses.

CHARLES FISHER.
